BY J. W. Bond

ATTY

UNITED STATES PATENT OFFICE.

AMOS A. CUSHMAN, OF SHREVE, OHIO, ASSIGNOR OF ONE-HALF TO LORENZO D. PATTEN, OF MANSFIELD, OHIO.

KITCHEN-CABINET.

SPECIFICATION forming part of Letters Patent No. 633,754, dated September 26, 1899.

Application filed January 7, 1899. Serial No. 701,477. (No model.)

To all whom it may concern:

Be it known that I, AMOS A. CUSHMAN, a citizen of the United States, residing at Shreve, in the county of Wayne and State of Ohio, have invented certain new and useful Improvements in Kitchen-Cabinets; and I do hereby declare that the following is a full, clear, and exact description of the same, reference being had to the annexed drawings, making a part of this specification, and to the figures of reference marked thereon, in which—

Figure 1 is a perspective view showing the different doors open. Fig. 2 is a view showing the interior of the proof-box, also showing the lamp-chamber. Fig. 3 is a view showing a portion of the cabinet, also showing the proof box or chamber and illustrating the location of the different air passages or chambers.

The present invention has relation to kitchen-cabinets; and it consists in the different parts and combination of parts hereinafter described, and particularly pointed out in the claim.

Similar numerals represent corresponding parts in all the figures of the drawings.

In the accompanying drawings, 1 represents the frame of the upper section of the cabinet, which is constructed in the ordinary manner and is provided with any desired number of compartments arranged for reception of various kinds of groceries or other articles.

If desired, one side of the upper section of the cabinet may be provided with the flour-compartment 2, the bottom or lower end of which may, if desired, contain an ordinary flour-sifter, which is operated by the crank 3.

The construction of the flour-sifter is not illustrated, as it forms no particular part of the present invention.

The upper section 1 of the cabinet proper is preferably made so that it can be detached at the point 4 and is so formed for convenience in handling.

For the purpose of providing an air-chamber between the bottom of the section 1 and the top of the proof-box 5, the bottom 6 of the cabinet-section 1 is located a short distance above the bottom or lower ends of the back and ends of the cabinet-section 1 proper, as

illustrated in Fig. 3, by which arrangement the heat from the proof-box will be cut off.

The lower section 7 may be substantially of the form shown in the drawings, and, as shown, it forms a support for the upper section of the cabinet.

The lower section 7 is divided into two compartments 8 and 9, said compartments being located and arranged substantially as shown in Fig. 1. The upper compartment of chamber 8 is provided with any desired number of shelves, such as 10, which shelves are preferably formed of suitable bars or slats, by which arrangement heat can be conveyed or passed through the supporting-shelves 10. Below the proof-box 8 is located the chamber 9, which chamber is so constructed that a lamp, such as 11, can be placed therein. For the purpose of providing an air-chamber between the walls of the lower section 7 and the proof-box or chamber 8 said proof-box is formed of less size than the size of the chamber in which it is to be contained or placed, or, in other words, the ends and side 12 are located and arranged substantially as shown in the drawings, by which arrangement the air-chambers 13 are formed.

Below the proof-box proper is located the partition 14, which partition is connected to the lower section 7 in any convenient and well-known manner, and, as shown, it is provided with an opening, such as 15, which opening is to receive the top or upper end of a lamp-chimney, as illustrated in Fig. 2. The bottom 16 is located a short distance above the partition 14. The bottom 16 is provided with the cup-shaped portion 17, which is located directly over the opening 15 and is so located for the purpose of bringing it directly above the top of the lamp-chimney.

The object and purpose of the cup 17 is to hold a quantity of water from which steam can be generated from the water contained in the cup 17.

The object and purpose of providing steam is to moisten the bread or other articles designed to be placed in the proof-box.

It will be noticed that the steam generated will be contained in the proof-box, and the heat generated by means of the lamp is free to pass around the proof-box, by which ar-

- angement the proper amount of heat and moisture is provided for the purpose of raising bread or light articles. For the purpose of allowing the heat to escape apertures, such as 18, are formed in the upper end of the section 7. Said apertures may be located as shown in the drawings, and, as shown, they are located or formed through the material composing the lower section.
- 10 In use I prefer to construct a cabinet proper of sheet metal, except the bottom of the chamber 9, which may be of wood. It will be understood that by constructing the cabinet of sheet metal it will not become tainted from use, and when the proof-box is in use as a dough-raiser it can be used for a receptacle and the articles contained therein will not be liable to mold.
- 15 For the purpose of closing the cabinet doors—such as 19, 20, 21, and 22—are provided, and for the purpose of inspecting the condition of the bread or other articles being raised the doors 21 should be provided with a glass, so that the door need not be 20 open and by which arrangement the bread will not be exposed to a cold draft of air.

It will be understood that a door or cover, such as 23, should be attached to the top or upper end of the flour-bin, which door may be of any ordinary construction.

Having fully described my invention, what I claim as new, and desire to secure by Letters Patent, is—

The combination of the proof-box provided with the compartments 8 and 9 one located above the other, and the upper one provided with shelves, the partition 14 provided with an opening, the bottom 16 provided with the cup or recessed portion 17 located directly over the opening 15, air-chambers located at 20 the back, bottom and ends of the proof-box doors hinged to the section 7, and air-passages 18, substantially as and for the purpose set forth.

In testimony that I claim the above I have 25 hereunto subscribed my name in the presence of two witnesses.

AMOS A. CUSHMAN.
